(57) **CLAIM**

The ornamental design for a weight plate, as shown and described.

DESCRIPTION

FIG. 1 is a front view of a first embodiment of a weight plate showing our new design, the rear view being identical to the front view;

FIG. 2 is a side view thereof;

FIG. 3 is a perspective front view of the weight plate as seen from above;

FIG. 4 is a front view of second embodiment of a weight plate showing our new design, the rear view being identical to the front view;

FIG. 5 is a side view thereof; and,

FIG. 6 is a perspective front view of the weight plate as seen from above.
